[57] CLAIM

The ornamental design for a training harness for track and field athletes, as shown and described.

DESCRIPTION

FIG. 1 is a front perspective view of a training harness for track and field athletes showing my new design; FIG. 2 is a side elevational view thereof, the side opposite being substantially a mirror image; FIG. 3 is a front elevational view thereof; FIG. 4 is a top plan view thereof; FIG. 5 is a bottom plan view thereof; FIG. 6 is a rear elevational view thereof; and, FIG. 7 is another side elevational view thereof with the L-shaped strap and cuff members removed.

The broken line showing of the human figure in FIG. 2 is for illustrative purposes only and forms no part of the claimed design.
